UNITED STATES PATENT OFFICE.

WILLIAM C. DEVEREAUX, OF DETROIT, MICHIGAN, ASSIGNOR TO FERRO STAMPING & MFG. COMPANY, OF DETROIT, MICHIGAN, A CORPORATION OF MICHIGAN.

HANDLE.

Application filed January 12, 1925. Serial No. 1,976.

This invention relates generally to handles and refers more particularly to vehicle door handles.

One of the essential objects of the invention is to provide a handle of this type that is built-up of a plurality of members, preferably stampings, which may be easily and quickly assembled to provide the finished article.

Another object is to provide a built-up handle that possesses all of the advantages of the handles now in use but can be produced at considerably less cost.

Another object is to provide a handle having trim and distinct lines which are obtained as a result of the uniformity in manufacturing the several parts of the handle.

With the above and other objects in view the invention consists in certain novel features of construction, combinations and arrangements of parts as will be more fully described and particularly pointed out in the appended claims.

In the accompanying drawing;

Figure 1 is a perspective view of a handle embodying my invention before the parts thereof are assembled.

Figure 2 is a perspective view of the handle after the parts are assembled.

Figure 3 is a cross sectional view through the handle before the flanges of the cover plate are bent inwardly.

Figure 4 is a bottom plan view of the finished handle.

Referring now to the drawing, the numeral 1 designates an operating shank or spindle to which a handle 2 embodying my invention is preferably secured.

As shown, the handle referred to is made up of a plurality of sheet metal sections, preferably four, of which one section 3 thereof is employed as an anchorage member for the others and is rigidly secured to the shank. The numeral 4 represents another section which is non-rotatably sleeved on the shank against the section 3 and constitutes a reinforcing member for the handle. 5 and 6 respectively designate the outer handle sections which are pressed to the form desired and jointly conceal the sections 3 and 4 respectively. As shown, the section 5 is non-rotatably sleeved upon the shank 1 against the reinforcing section 4, while the section 6 is preferably mounted on the an-

chorage section 3, and is provided with transversely extending side and end flanges 7 and 8 respectively that constitute a housing for the sections 3 and 4 respectively as well as the section 5. For securing the handle sections together, the free edges of these flanges 7 and 8 respectively are preferably turned inwardly against the outer face of the section 5. In order that the handle will be comfortable to grasp and at the same time will be strong and durable, the sections 5 and 6 are preferably curved transversely outwardly and are provided with plated or otherwise finished exterior surfaces. The section 3 is also preferably curved transversely outwardly to constitute a backing for the section 6 while the opposite end portions 9 of the section 4 are preferably curved, transversely outwardly to form a backing for the section 5. The section 6 is also preferably provided with rounded edge portions that merge into the flanges 7 and 8 respectively.

In the process of construction, the section 3 is anchored first upon the shank 1, the sections 4 and 5 respectively are then sleeved upon the shank in the order named, and the section 6 is subsequently mounted on the section 3. The edges of the flanges 7 and 8 respectively are then bent inwardly to hold the parts together.

It is usual in most instances to plate the handles, and in the form described there is the likelihood of fluid entering the handle interior during the plating operation. A suitable drain opening as 10 is therefore provided in the handle, preferably in the section 5 as shown, to permit of the escape of trapped fluid. Any remaining moisture is removed by the heat present in the finishing operations of the article.

From the foregoing description it will be readily apparent that a handle of the type described, while possessing the essential requisites of a handle of standard construction may be produced at considerable lower cost. Further, through the stamping operation employed, not only is uniformity in product secured, but more definite and distinctive lines given to the finished article producing a more attractive and pleasing appearance.

What I claim as my invention is:

1. The combination with a spindle, of a built-up all metal handle including a re-

- inforcing member sleeved upon said spindle, a transversely curved anchorage member rigidly secured to the top of said spindle and having the longitudinal edges thereof engaging one face of said reinforcing member, a transversely curved finishing plate sleeved upon said spindle and having the longitudinal edges thereof bearing against the opposite face of said reinforcing member, and a trough-shaped shell snugly receiving said reinforcing member, anchorage member, and finishing plate and having a transversely curved top portion closely embracing said transversely curved anchorage member, said shell having side and end portions which are adapted to be bent inwardly for clamping said members and plate within the shell. 30
3. The combination with a spindle of a built-up handle including a substantially flat reinforcing member sleeved upon said spindle, a transversely curved resilient anchorage member rigidly secured to the top of said spindle and having the longitudinal edges thereof engaging one face of said reinforcing member thereby spacing the major portion of said anchorage member from the reinforcing member, and a trough-shaped shell snugly receiving said reinforcing and anchorage members and having portions which are adapted to be bent inwardly for clamping said members within the shell. 35
2. The combination with a spindle, of a built-up handle including a reinforcing member sleeved upon said spindle, a transversely curved resilient anchorage member rigidly secured to the top of said spindle and having the edges thereof engaging one face of said reinforcing member, a resilient finishing plate transversely curved in a direction opposite to said anchorage member and having the edges thereof bearing against the opposite face of said reinforcing member, 40
- 25

In testimony whereof I affix my signature.

WILLIAM C. DEVEREAUX.
